UNITED STATES PATENT OFFICE.

THEODORE LIVINUS REEPMAKER D'ORVILLE, OF TWICKENHAM, ENGLAND.

INTERNAL-COMBUSTION ENGINE.

1,269,264.

Specification of Letters Patent. Patented June 11, 1918.

Application filed June 4, 1917. Serial No. 172,716.

To all whom it may concern:

Be it known that I, THEODORE LIVINUS REEPMAKER D'ORVILLE, a subject of the Queen of the Netherlands, and resident of Twickenham, county of Middlesex, England, have invented a certain new and useful Improvement in Internal-Combustion Engines, of which the following is a specification.

This invention relates to improvements 10 in four-stroke cycle internal combustion engines working with supercharge, said supercharge being composed either of air, combustible mixture or burnt gases, and wherein the valves are constituted by a sleeve or 15 sleeves coaxial with the cylinder. One object of the present invention is to provide an engine of the kind referred to in which it is possible to augment the torque on the engine crank shaft either by an augmented 20 working charge per cycle of operations or by increasing the initial pressure of the working fluid at the end of the first stroke (suction) by the introduction of slightly compressed air or inert exhaust gases.

25 In the case of engines used for aircraft, the above-mentioned object may be used as a means for power recuperating in high altitude flight, as is well known under these circumstances the ordinary four stroke engine suffers loss of power owing to reduced 30 weight of charge entering the cylinder under natural suction on the one hand and invariable compression ratio on the other, causing a gradual drop of the compression and explosion pressures.

Another object is to provide the necessary 40 means for evacuating the increased amount of exhaust gases due to the supercharge, and toward this end a duplicated exhaust is provided, the second exhaust being timed 45 simultaneously with the first exhaust and not governed by the top edge of the piston uncovering slots in the cylinder wall toward the end of the exhaust stroke. The 50 last named means, apart from upsetting the cycle of operations at the end of the suction stroke, when communicating with the exhaust is undesirable, has the grave disadvantage of permitting the rush of hot gases 55 along the piston head. With the proposed timing of the supplementary exhaust these conditions do not obtain, the piston head will therefore not be burned and the piston rings are cooler and will not so readily become carbonized.

The provision of the aforementioned du-

plicated exhaust further permits of uncoving the exhaust ports later than would otherwise be permissible. The increased facilities for evacuation of burnt gases thus 60 allow for an increased expansion stroke without danger of creating back pressure on the exhaust stroke, and the gas pressures and temperatures will in consequence be lower on opening of the valves, this point 65 being beneficial to long life of port edges.

A further object of the present invention is to avoid leakage of fluid from the cylinder to the engine crank case along the piston and sleeves by the means hereinafter to be 70 described, in order to avoid waste.

In this type of engine the increased amount of thermal units to be disposed of to the air and also to the cooling medium in the jackets surrounding the cylinders, 75 calls for the use of a better heat-conducting metal for pistons and cylinders than the usual cast iron, and it is proposed here to utilize the presence of the sleeve or sleeves, at least when said sleeve or sleeves is or are 80 arranged inside the cylinders, to make the pistons and cylinders of aluminium alloy, leaving the sleeve or sleeves of harder metal, for instance, chilled iron, gun-metal or bronze. The use of aluminium alloy further 85 results, as a side issue, in decreasing the engine weight for a given size and power.

For the above purposes a four stroke cycle internal combustion engine according to the present invention comprises parts which are 90 so combined and arranged as to enable the above mentioned objects to be successfully attained. Where it is desired to supercharge with compressed air or combustible mixture the improved engine comprises in 95 addition to the engine cylinder and piston, a pump or compression chamber independent of the crank chamber in which the charge-augmenting fluid is compressed, a receiver into which the compressed charge-augmenting fluid is delivered and held until required for use, a sleeve valve coaxial with the engine cylinder and adapted to control the passage of the compressed charge-augmenting fluid from the receiver 100 to the engine cylinder and means for actuating the said valve. The passage of the charge-augmenting fluid into the pump chamber and from that chamber into the receiver is also controlled by a sleeve valve 105 coaxial with the engine cylinder and which may with advantage be the same valve as

that used to control the passage of the fluid from the receiver to the engine cylinder. Further, the supplementary exhaust from the engine cylinder is also controlled by a sleeve valve, coaxial with the engine cylinder and this again may advantageously be the same valve as that used for the aforementioned controls. The pump chamber may be formed in known manner by and between the engine cylinder, the piston, a skirt or trunk on the piston of less diameter than the piston, forming a crosshead and a stationary ring within the cylinder or valve forming a crosshead guide, the pump chamber thus is of annular shape. The ports in the controlling valve or valves are so arranged that the successive supplementary charges of compressed fluid within the receiver will be held therein until the engine piston nears the end of its suction outstroke, whereupon the supplementary charge of fluid will be admitted to the engine cylinder for the purpose of increasing the charge already in the cylinder and also the initial pressure thereof before compression takes place in the engine cylinder, for the purpose in any case of increasing the torque on the engine crank shaft as previously stated.

In case it is desired to supercharge with exhaust gases, previously cooled down to a suitable temperature, either the aforementioned means may be employed, the pump then compressing burnt gas into the receiver, or else a suitable amount of exhaust gas may be admitted directly to the receiver at the required pressure there to be cooled and held until required for further use as before. In this latter case the use of the pump may be advantageously dispensed with.

Having set forth generally the improvements to be attained in order to secure the beforementioned objects, the means employed toward accomplishing such end will now be described and illustrated by the accompanying sheet of drawings. Of the drawings:—

Figure 1 is a vertical section.

Fig. 2 is a sectional plan view showing the two suction or inlet ports and the delivery port of the compressor or pump.

The pump inlet ports a^3 communicate either with a carbureter through a pipe b provided with a throttle c regulating the amount of mixture sucked up by the pump d , or otherwise ports a^3 communicate with the exhaust piping; or lastly with the atmosphere according as to whether, fresh mixture, exhaust gases or pure air be selected for the supercharge. By altering the volumetric efficiency of the pump by means of throttle e , the receiver pressure may be varied and consequently the actual amount of supercharge to the engine cylinder.

Where a common carbureter is used to sup-

ply mixture to both cylinder a and pump d as indicated in the example shown, a main throttle on the carbureter (not shown) delivery pipe regulates the amount of mixture to both, whereas throttle c merely acts on the pump.

In the example shown, the engine or working cylinder a has the ordinary inlet port a' and exhaust port a^2 at its combustion chamber end and further suction ports a^3 , a^4 and delivery port e to the pump besides a transfer port f from the receiver f' to the engine cylinder toward its crank chamber end.

Midway between these sets of ports is situated the supplementary or duplicate exhaust p which is timed so as to uncover at the same time as the ordinary exhaust a^2 , a^2 . This supplementary exhaust port is so disposed that it is never uncovered by the piston skirt and the lower piston ring always seals the annular pump space from the exhaust.

The piston a^4 is formed with a skirt or trunk a^5 that is of less external diameter than the internal diameter of the cylinder and sleeve valve or valves and serves as a crosshead through a guide ring m fixed within the cylinder so as to form with the cylinder piston and crosshead guide ring 95 an annular pump chamber d^* . The fluid admitted at each instroke of the piston will be compressed at the next outstroke and delivered through the outlet port e into a receiver from which it can pass through the transfer ports f into the working cylinder.

The ports a^3 , a^4 , e , p , a' , a^2 , are controlled by a compound cylindrical ported slide valve comprising in the example two sleeves h and i arranged concentrically with each other and with the engine cylinder either within or outside the latter. As the sleeves h and i are operated by a half time shaft, the same ports in the sleeves and cylinder will not serve at each revolution as fluid inlet and delivery ports for the pump, they are therefore duplicated either in one or two sleeves or in the cylinder. In the example shown the sleeves h and i are respectively formed with ports h' and i' for controlling the admission of fluid to the pump chamber d^* with a set of ports h^2 and i^2 for controlling the admission of compressed fluid from the pump chamber b^* to the receiver f with a set of ports h^3 , i^3 for controlling the transfer of compressed fluid from the receiver f' to the engine cylinder through the ports therein and with a set of ports p' , p^2 for controlling the duplicate or additional exhaust p from the engine cylinder. The sleeves h , i which in the example are also respectively provided with a set of inlet ports h^4 and i^4 and a set of exhaust ports h^5 and i^5 arranged to control the main inlet and exhaust ports a' and a^2 of the cylinder, are re-

ciprocated by rods j and j' from two crank pins j^2 and j^3 . These pins are arranged with their center 90 degrees apart and connected to a shaft j^* that is rotated by any convenient means from and at half the speed of the crank shaft j^4 , the crank pin j^2 being arranged so as to be in the same angular position as the engine crank pin j^5 when this is at the end of the compression strokes, the crank pin j^3 being arranged about 90 degrees behind the crank pin j^2 .

With reference to the drawing it will be seen that with inlet passages h' , i' to the pump are so arranged that any leakages along the cylinder walls and sleeves h and i will not go to waste but are caught up in an annular space k leading to a well k' in the top of and exterior to the crank case k^2 , to be used on the next stroke, the sleeve ends and actuating gear thereof moving in said annular space and well, the wall k^3 of the said annular space k' forming part of the cylinder and separable from the crank case k^2 . The pipe b is bolted to the wall k^3 and rings m' of either the expanding or contracting type are employed in the cylinder wall and cross-head guide ring extension n forming part of the pump, to seal the compressed fluid and prevent the same escaping in either an upward or downward direction.

Having now described my invention, what I claim as new and desire to secure by Letters Patent of the United States is:—

1. A four cycle internal combustion engine including a cylinder having upper and lower fuel intake ports and a plurality of exhaust ports, an annular abutment within the cylinder, a piston adapted to coöperate with the head of the cylinder to form a working chamber in communication with the upper fuel intake port and the exhaust ports and also coöoperating with said abutment to provide a compressor chamber, a receiver adapted to communicate with the latter on the down stroke of the piston, and a casing formed at the lower end of the cylinder and in communication with the lower fuel intake port thereof, and said casing adapted to communicate with the compressor chamber on the up stroke of the piston.

2. A four cycle internal combustion engine including a cylinder having a main fuel intake port and exhaust ports and an auxiliary fuel intake port, and means for injecting a supplementary fuel charge into the main charge at the end of the suction stroke including a fixed abutment within the cylinder, a piston coöoperating therewith, an initial fuel receiving chamber communicating with said auxiliary fuel intake port, a valve to establish communication between

the latter chamber and the space between the piston and the abutment on the compression stroke of the piston, a receiver, and sliding valve means including the valve 65 above mentioned adapted to establish communication between the compression chamber formed by the piston and the abutment and the receiver, and also between the latter and the working chamber of the cylinder. 70

3. A four cycle internal combustion engine including a cylinder having a main fuel intake port and a plurality of exhaust ports, a crank case for supporting said cylinder and having a portion projecting up 75 into the cylinder to provide a combined piston guide and interior abutment and also providing an annular auxiliary fuel receiving chamber, a piston working in the cylinder between the abutment and the main fuel 80 intake port, a receiver, concentric sleeve valves slidably arranged between the upstanding portion of the crank case and the cylinder and having ports for controlling the main intake and exhaust ports and also 85 controlling the communication between the annular auxiliary fuel receiving chamber and the space between the piston and the abutment, and also the communication between the latter space and the receiver, and 90 operating means for said valves housed within the annular auxiliary fuel receiving chamber.

4. A four cycle internal combustion engine including a cylinder having a fixed 95 head and inlet and exhaust ports adjacent thereof, a fixed abutment ring arranged in the lower part of the cylinder, a piston working between the fixed cylinder head and fixed abutment ring and forming a compressor chamber, an auxiliary fluid receiving chamber formed at the lower end of the cylinder and including a closed well portion, valves for controlling the inlet and exhaust ports of the cylinder and also the 100 inlet and exhaust ports of the compressor chamber, operating mechanism for the valves located in the aforesaid well, and a compressed fluid receiving chamber located exterior of the chamber and having spaced 105 inlet and discharge ports adapted to respectively communicate with the compressor chamber and with the interior of the working cylinder at different points in the cycle of operation of the engine. 110

In testimony whereof I have affixed my signature in presence of two witnesses.
